Patented June 27, 1916.

UNITED STATES PATENT OFFICE.

OLIVER E. MONROE, OF ST. LOUIS, MISSOURI.

WIRE LIFTER AND SPACER.

1,189,161.

Specification of Letters Patent. Patented June 27, 1916.

Application filed March 30, 1915. Serial No. 18,115.

To all whom it may concern:

Be it known that I, OLIVER E. MONROE, a citizen of the United States, residing at St. Louis, State of Missouri, have invented certain new and useful Improvements in Wire Lifters and Spacers, of which the following is a specification.

As is quite well known generally, it often becomes necessary to renew insulators carried by the cross arms of telegraph poles as well as to take up slack in the strung wires, necessitating that the linemen come into more or less intimate contact with the conductors in carrying out their duties which 10 become extremely hazardous if said conductors involve those employed in high tension service. As a matter of fact, to enable repair or replacements to be accomplished, it is not unusual that the current is turned off 15 accompanied by a cessation of service and expensive delays to consumers.

To obviate these difficulties or disadvantages is the object of my present invention which enables the linemen to operate at 20 a distance, manipulating the wires and holding same spaced from the cross arm while the insulator is replaced or removed, as the case may be.

The invention comprises a rod having a 25 wire engaging and holding element at its upper extremity and adjustable supporting means intermediate its length for attaching the rod to a cross arm temporarily in order to hold the wire spaced therefrom during 30 manipulation of the insulators.

With the above and other objects in view, this invention consists in the construction, combination and arrangement of parts all as hereinafter more fully described, and 40 illustrated in the accompanying drawing, wherein:

Figure 1 is a view showing the apparatus of my invention in use as applied to a telegraph pole for holding the wire spaced from 45 the cross arm. Fig. 2 is a side elevation of the implement comprehended by my invention. Fig. 3 is a front elevation thereof. Fig. 4 is an enlarged sectional view taken on the line 4-4 of Fig. 3. Fig. 5 is a detail 50 view of the wire guard and guide elements of the wire engaging member forming a part of my invention.

Throughout the following detail description, and on the several figures of the drawing, similar parts are referred to by like reference characters.

Referring to the drawing, and specifically describing my invention, the numeral 1 designates a rod or stick preferably rectangular in cross section and of a suitable length for best carrying out the function comprehended by this invention. The lower extremity of said rod has secured thereto a hand grip 2, preferably of insulating material such as rubber or the like. The upper 60 end of the rod has disposed thereon an insulator 3 of any desired form or configuration having a groove 4 extending transversely thereof and constituting a wire receiving seat. Connected to this insulator 70 is a wire engaging guide and guard which comprises two coöperating members 5, 6, the former consisting of a semi-circular base 5' having offstanding apertured extremities conforming to the base 6' and extremities of 75 the member 6 whereby to enable the guard to be attached in position upon the insulator, as by means of fastening bolts 7 passing through the aforesaid apertured extremities.

Projecting upwardly and bending inwardly along the line of the insulator surface is a guide finger 5^a, terminating just slightly overhanging the groove 4 of the insulator. From the opposite member 6 extends upwardly an overhanging guard arm 80 85 6^a which projects over and in spaced relation to the guide finger 5^a, terminating approximately opposite the base 6'. It will be apparent that when this element of the device is engaged with a wire, the latter 90 passes upwardly between the finger 5^a and arm 6^a, being guided over the former into the groove 4 from which it is incapable of being accidentally displaced by swinging or jarring of the conductor or wire. Incidentally the member 6 is formed with an inner shoulder 6^b assisting the passage of the wire into the groove 4 as aforesaid.

The second feature of this device is the adjustable supporting means mounted on 100 the rod which consists of a clamping sleeve 8, rectangular in cross section to conform to the shape of the rod, and having a longitudinal slot 9 at opposite sides of which slot is provided projecting apertured lugs 10, 10 105 through which fastening members or bolts 11, 11 extend for clamping the sleeve to the rod. On the opposite side, the sleeve 8 is recessed as at 12, and said recess is of sufficient depth to receive a circular plate 13 rotatably mounted in the recess on a pivot 14 secured 110 to the body of the sleeve as best disclosed in

Fig. 4 of the drawing. Offstanding from this plate are a pair of spaced apertured ears 15 in which is pivotally mounted a relatively large hook 16, of sufficient size to be engaged over a conventional cross arm of a telegraph pole in a manner disclosed in Fig. 1. The inner and upper portion of this hook is toothed or serrated as at 17 to prevent the hook from slipping. This hook may be said 5 to have a triple adjustment or movement,— first, a pivotal movement on its pivot 16', a rotatable movement on the pivot of the plate 13, and a longitudinal movement on the rod through adjustment of the sleeve 8. Many 10 advantages accrue to such an arrangement and especially with respect to adequate control of the space or distance at which the wire engaged in the wire engaging member may be held from the cross arm.

20 To prevent rotation of the plate 13 and pivotal movement of the hook 16 when it is desired to engage the latter over a cross arm from a position beneath said arm, the sleeve 8 is formed with an upward extension 18 25 having outwardly projecting spaced friction gripping elements 19 between which the hook is received and held in accomplishing the above attachment.

30 Retaining plates 20 and 21 are attached to the sleeve 8 by means of screws, one plate at each side of the member 13 over which they extend a sufficient distance to hold the plate in its rotative movements and prevent the same from binding at the top or the 35 bottom.

In the use of the device the lineman after 40 ascending the pole to within a suitable distance from the cross arm inserts the arm 6 of the wire engaging member at the upper extremity of the rod over the wire to be displaced, engaging said wire in the seat or groove 4 whereupon it is lifted to a sufficient height to enable the hook 16 to be engaged over the cross arm of the pole. The lower 45 end of the rod is then preferably strapped to the pole, leaving the lineman free to manipulate the insulator to be removed or replaced as the case may be, the handling of said insulator being accomplished by means of a 50 special tool or implement forming the subject-matter of a separate application. With this arrangement the lineman does not need to come into physical contact with the live wires carrying high tension currents either 55 in displacing them or application of an insulator or tying said wires in proper position, nor is it requisite that the current be turned off during repairs or such replacements as mentioned.

60 As hereinbefore premised, to regulate the spacing of the wire from the cross arm, it is only necessary to adjust the sleeve 8 upwardly or downwardly on the rod 1 in an obvious manner.

65 I desire not to be limited to the exact con-

figuration or details of construction disclosed by the drawing in this application since it is within the scope of the appended claims and spirit of the present invention to make slight changes in the details of construction. 70

Having thus described my invention, what I claim as new is:

1. In a device of the class described, a support, a wire engaging element thereon 75 comprising a seat for receiving the wire, and a guard on said engaging element for preventing displacement of the wire, including a member extending over the seat in spaced relation thereto and transversely 80 of the wire when disposed in the seat, the member having a downwardly bent portion so arranged as to provide a lateral entrance to the seat.

2. In a wire lifter and spacer, the combination of a lifting member, a wire engaging element carried at one end thereof, a freely rotatable supporting member pivotally mounted on said lifting member, means for adjusting said supporting member on the 90 lifting member, and friction means for holding the said member from accidental rotation.

3. In a wire lifter and spacer, the combination of a lifting rod, a wire engaging 95 member mounted thereon at one end and insulated therefrom, and supporting means for holding the rod at a predetermined position comprising a sleeve clamped to the rod, and a support engaging member swiv- 100 elly connected to said sleeve.

4. In a wire lifter and spacer, the combination of a lifting rod, a wire engaging member mounted thereon at one end, supporting means for said rod comprising a 105 sleeve, means for holding said sleeve at adjusted positions, a support engaging hook, a connecting member having revoluble connection with the sleeve for rotation in planes parallel to the rod, and a pivotal connection 110 on said connecting member for connecting said hook thereto.

5. In a wire lifter and spacer, the combination of a lifting member, a wire engaging member carried at one end thereof, 115 supporting means adjustably connected to said member and comprising a sleeve adjustable toward and from the wire engaging member, a supporting hook swingingly mounted on said sleeve, and retaining means 120 for said hook for holding the same in operative position, preliminary to engagement thereof with a support for said lifting member.

6. In a wire lifter and spacer, the combination of a lifting member for the manipulation of wires, supporting means for holding said lifting member in a predetermined position, and a wire engaging element at its extremity comprising an insu- 125 130

lating member secured to said lifting member and formed with a wire receiving seat, and guard means connected to said insulating member for guiding the wire into and preventing displacement of said wire from the seat aforesaid.

7. In a wire lifter and spacer, the combination of a lifting member for the manipulation of wires, supporting means for holding said lifting member in a predetermined position, a wire engaging element comprising an insulating member having a wire receiving seat, and guard means cooperating therewith for preventing acci-

dental displacement of the wire from said seat, the guard means consisting of an arm overhanging the seat, and a clamping element for attaching said guard member to the insulating member and having a guiding finger arranged to cooperate with the overhanging arm substantially as specified.

In testimony whereof I affix my signature in presence of two witnesses.

OLIVER E. MONROE.
